LIGHT EMITTING GAS DISCHARGE MATRIX DISPLAY PANEL

William D. Petty, 524 Clover Lane, Perrysburg, Ohio
43551, and Larry J. Lohmann, 2416 Oak Grove Place,
Toledo, Ohio 43613

Filed Aug. 6, 1973, Ser. No. 386,126

Term of patent 14 years

Int. Cl. D14—02

U.S. Cl. D26—5 C

FIG. 1 is a front elevational view of a light emitting gas discharge matrix display panel embodying our new design, the rear being a mirror image of the front shown;

FIG. 2 is a bottom plan view thereof, the top being the same as the bottom shown; and

FIG. 3 is an elevational view taken from one side thereof, the opposite side being a mirror image of the side shown.

We claim:

The ornamental design for a light emitting gas discharge matrix display panel, as shown and described.
